UNITED STATES PATENT OFFICE.

SAMUEL P. BUSH, OF COLUMBUS, OHIO, ASSIGNOR TO THE BUCKEYE STEEL CASTINGS COMPANY, OF COLUMBUS, OHIO.

CAR TRUCK.

Application filed July 20, 1926. Serial No. 123,719.

This invention relates to car trucks and especially to cast steel side frames therefor, one object of the invention being to reduce the length of the lower or tension member which is unsupported between the columns, and also reduce the width and weight of the spring plank. Another object is to arrange the springs in a novel manner and dispose the load on the lower member of the side frame in a more satisfactory manner than has been heretofore done. Other objects of the invention will appear in the course of the following description, and the invention resides in certain novel features which will be particularly pointed out in the appended claims.

In the annexed drawing,

Figure 1 is a view partly in top plan and partly in horizontal section;

Figure 2 is a view partly in side elevation and partly in section of a portion of a truck illustrating the invention.

Figure 3 is a view similar to Figure 1 but showing a different arrangement of the springs.

The reference numeral 1 indicates the bolster, 2 the spring plank, and 3 the side frame, the side frame being cast in one integral structure having an upper compression member 4, a lower compression member 5, and columns 6. The several members of the side frame define a central opening through which the ends of the bolster and the spring plank are received, and journal boxes are also preferably formed integral with the side frame at the junction of the compression and tension members.

According to the present invention, the opposed sides of the columns have their lower portions projected within the opening for the bolster in downwardly converging relation, as at 7, the opening, consequently, being smaller at bottom than at the top instead of larger at the bottom as was the general practice heretofore. The distance between the lower ends of the columns being thus reduced from standard practice, the length of the lower member unsupported between the columns is shortened and the strength of the frame is correspondingly increased. The lower central portion of the tension member is substantially V-shaped with obtuse angle and the spring plank has a cross-sectional outline corresponding to the upper side of the tension member and is held against move-

ment across the side frame by inter-engaging studs and sockets, as indicated at 8 or other inter-engaging means. Near the base of each column, a spring seat 9 is formed between the side flanges of the column over the tension member, said seat defining shoulders 10 formed by the lower portions of the columns and extending approximately to the same level as the top of the spring plank. The flange 11 of the spring seat is arcuate so that it fits partly around the spring on the adjacent seat 9 as will be understood. The spring plank rests on the tension member between the shoulders 10 and is effectually held against movement relative to the side frame.

The springs 12 are arranged in two intersecting series, one series extending longitudinally of the spring plank and the other series extending longitudinally of the side frame. In the arrangement shown in Figure 1, a spring is placed upon each spring seat 9 and two springs are placed on the central longitudinal line of the spring plank, the springs in each series fitting partly between the springs in the other series. The bolster, of course, extends over and rests upon all the springs. By thus arranging the springs, the outer springs on the tension member are brought partially, if not wholly, within the lines of the columns and a more efficient support for the tension member is provided than if the spring loads were carried entirely between the columns as heretofore. The transverse stresses on the tension member between the columns are greatly reduced as well as the secondary stresses thereby set up which disadvantageously affect the tension member beyond the columns in the direction of the journal boxes.

In Figure 3, an arrangement of five springs is shown, one spring being common to both series and being the centre of the group. With this arrangement, the bolster is somewhat longer than in the arrangement shown in Figure 2 and both the bolster and the spring plank project a somewhat greater distance from the side frame but, otherwise, the construction is the same.

Having fully described my invention what I claim as new and desire to secure by Letters Patent, is:—

1. In a car truck, the combination of a side frame, springs, and a bolster, said side frame comprising upper and lower members and columns defining a central opening, the

- side walls of the upper portion of said opening being parallel to accommodate the normal movements of the bolster, the side walls of said opening converging approximately 5 from lower limit of bolster movement toward the lower ends of the springs.
2. In a car truck, a side frame comprising an upper member, a lower member, and columns integral with the upper and lower 10 members and defining a central opening for bolster and springs, the opposed surfaces of the columns being parallel in their upper portions and converging downwardly in their lower portions, and the lower member having 15 spring seats thereon housed within the lower portions of the respective columns.
3. In a car truck a side frame comprising upper and lower members and columns, all cast integral, an opening between the columns 20 for springs and bolster and spring seats arranged partially within the lines of the columns extending upward from the upper surface of the lower member, said spring seats being approximately on the same level.
- 25 4. In a car truck a frame comprising upper and lower members and columns, all cast integral, an opening between the columns for springs and bolster and adapted to the location of springs partially within the lines of 30 the columns extending upward from the lower member and having spring seats for the outer or end springs above the upper line of the tension member.
5. In a car truck a side frame comprising 35 an upper member, a lower member substantially V-shaped, columns connecting the upper and lower members and spring seats within the columns, all cast integral and defining an opening between the columns for bolster 40 springs and a spring plank having end portions which on the under side are shaped to fit the contour of the central part of the lower member between the columns, the upper side 45 of said end portions being on approximately the same level with the said spring seats.
6. In a car truck a side frame comprising an upper member, a lower member substantially V-shaped, columns connecting the upper and lower members and spring seats within the columns all cast integral and defining 50 an opening between the columns for bolster springs and a spring plank having end portions which on the under side are shaped to fit the contour of the central part of the lower member between the columns, the upper side 55 of said end portions being on approximately the same level with the said spring seats above the upper line of the tension member.
7. In a car truck, a side frame comprising an upper member, a lower member substantially V-shaped, columns connecting the upper and lower members and defining an opening 60 between the columns for bolster and springs, a spring plank with end adapted to fit the contour of the lower member at the 65 central portion between the columns and a group of springs resting on the spring plank and on spring seats integral with the side frame, said springs being partially within the lines of the columns and substantially on 70 or above the level of the upper limits of the lower member between the columns.
8. In a car truck the combination of a side frame having a compression member, a tension member, and columns in an integral 75 structure defining a bolster and spring plank receiving opening, the columns having their lower side portions extended in downwardly converging relation, spring seats formed between the extended side portions of the respective columns, a spring plank engaged between the spring seats, and bolster-supporting springs on the spring plank and the spring seats, the springs on the spring seats being partly housed by the extended lower 80 portions of the columns.
- In testimony whereof, I have signed this specification.

SAMUEL P. BUSH.
